Primary Examiner — Michael C Stout*Assistant Examiner* — Tia Ruth-Renee Polidori(74) *Attorney, Agent, or Firm* — K&L Gates LLP(57) **CLAIM**

The ornamental design for a drinking vessel, as shown and described herein.

DESCRIPTION

FIG. 1 is a top perspective view of my new design for a drinking vessel;

FIG. 2 is a bottom perspective view thereof;

FIG. 3 is a side view thereof;

FIG. 4 is a top view thereof;

FIG. 5 is a bottom view thereof; and,

FIG. 6 is a cross-sectional view thereof taken along line 6-6 in FIG. 4.

The portions of the drinking vessel shown in broken line form no part of the claimed design.

1 Claim, 6 Drawing Sheets(56)
